George Stoudinger. Newark N.J.

Letters Patent.

Of the Schedule referred to in these Letters Patent
and making part of the same, containing a description in
the words of the said George Stoudinger, himself of his improve-
ment in the machine for edging and drawing steel points
for carriage springs.

To all to whom these presents shall come.

Be it known that I, George Stoudinger, of Newark in the County
of Essex, and state of New Jersey, have invented a new
and useful Machine for edging and drawing steel points
for carriage springs, and that the following is a full
and exact description of the construction and operation
of the said machine as invented by me.

N° 1. is a horizontal roller with three projections on, and
three grooves in, and on each end is a coupling, and
also a large wheel which the couplings so fit, as to put
it in and out of use.

N° 2. is a female die with grooves in, to correspond with the
projections, and grooves in the horizontal roller; said
grooves are to draw points from one inch up to three
inches in width and from one eighth of an inch up to
three quarters of an inch thick.

N° 3. is a carriage on which the female die is placed, the
die is raised to any height by six screws, which go through
the plate of the carriage, and also two backs, which fit
on the carriage on the outside of the frames, which
are driven from the big wheels on the ends of the two
horizontal rollers; the carriage when in gear forced

the point of the plate through, and by putting it out of gear it runs back by weights or a spring attached to the back part of the carriage. said carriage has right wheels under it with grooves in them, to correspond with the track on which they run.

N°. 4. are two bearings on which Number three runs.

N°. 5. are wheels which fit on under Number three.

N°. 6. are screws which raise the female die to any taper.

N°. 7. are couplings which fit in cog wheels, number eight.

N°. 8. are cog wheels which fit in racks to force the carriage forward.

N°. 9. are racks which fit on the outside of the carriage.

N°. 10. are frames in which the horizontal roller works.

N°. 11. is a lever - to put the couplings in and out of gear; said points are drawn by pulling the plate between the two horizontal rollers; and the female die, in the first place edge the point down a little, and then put it in the grooves of the female die, and put machine in gear which moves the carriage along, and forces the plate to a point.

The drawings on a scale of one quarter to the inch, accompany this specification, and are hereby so referred to. Said machine is all cast iron, except the screws.

To which specification, I have hereunto subscribed my name, in the presence of two witnesses, the twentieth day of December in the year of our Lord 1831, one thousand eight hundred and thirty.

Witnesses

Wm. Brewington,
Mrs. Worts.
